UNITED STATES PATENT OFFICE.

ADOLPH PESTER, OF BROOKLYN, ASSIGNOR TO THOS. NELSON & SONS, OF NEW YORK, N. Y.

BOOK-HOLDING DEVICE.

SPECIFICATION forming part of Letters Patent No. 273,886, dated March 13, 1883.

Application filed November 24, 1882. (No model.)

To all whom it may concern:

Be it known that I, ADOLPH PESTER, of Brooklyn, Kings county, New York, have invented certain new and useful Improvements 5 in Book-Holding Devices; and I do hereby declare the following to be a full, clear, and exact description of the same, reference being had to the accompanying drawings, which form a part of this specification.

10 My invention has for its object to cheapen the manufacture and increase the convenience in use of book-holding devices by simplifying the means and construction employed; and it consists generally in such combinations of the 15 covers of the books themselves with other parts as are hereinafter specifically described and claimed.

In the accompanying drawings, Figure 1 is a transverse section on the plane $x x$ of a device embodying my improvement in its preferred form, and Fig. 2 is a perspective view of the same.

Like letters of reference indicate like parts. A and B are the two books to be held. One 25 cover of the book A has on its outer surface the pocket a , which is adapted to receive one cover of the book B, as shown in the drawings. The other cover of the book A is provided with a clasp, b . The book B has one cover 30 that is adapted to be received into the pocket a on book A. The other cover of the book B is prolonged into a flap, c , which is adapted, in any usual way, to take over and be secured by the clasp b , as shown in the drawings.

35 C is a handle, which is of any usual construction and applied in any usual way. It may be employed or not, as desired.

D is a coin or currency pocket, which is shown in the drawings as being secured to the 40 inner surface of the cover whose prolongation forms the flap c . This coin-pocket may be secured to either cover of either book, preferably on the inner side of the same, so long as it does not interfere with the operation of the 45 pocket a , and is so placed as to have its opening or mouth upward when the books are being carried by means of the handle, so as there-

by to avoid the danger of dropping out and losing the contents of such coin-pocket. I prefer to employ both the handle C and the coin-pocket D in my device. 50

It is evident that the details of the device shown in the drawings may be varied without departing from the spirit of my invention. For example, the pocket a may be varied to 55 any extent in shape and form, and may be mounted rigidly or detachably, and on either book, so long as it furnishes the means of securing the two books together on their adjacent sides, substantially as is shown. The clasp b may be of any construction, and may 60 be mounted in any position on the outer surface of either outer cover, so long as it serves to clasp and hold the flap c ; and the flap c may be of any construction, and may be either 65 integrally or detachably a prolongation of either outer cover, so long as it holds the two outer covers of the two books together at a point opposite their backs when secured in operative position by the clasp b , substantially 70 as is shown.

What I claim as new, and desire to secure by Letters Patent, is—

1. The books A and B, having one of their adjacent covers provided with a pocket to hold 75 the other adjacent cover, and having one of their outer covers provided with a flap to take over and be secured by a clasp, substantially as and for the purposes set forth.

2. As a new article of manufacture, a book-holding device consisting of the book A, having a pocket, a , on the outer face of one cover, and a clasp, b , on the outer face of the other cover, and the book B, having one cover adapted to fit into the pocket a and the other cover 80 prolonged into a flap, c , to overlap and be secured by the clasp b , and provided with a handle, C, substantially as and for the purposes set forth. 85

ADOLPH PESTER.
